UNITED STATES PATENT OFFICE

2,259,998

AUTOMATIC GAIN CONTROLLED AMPLIFIER

George M. Brown, Scotia, N. Y., assignor to General Electric Company, a corporation of New York

Application July 23, 1940, Serial No. 346,948

5 Claims. (Cl. 179—171)

My invention relates to amplifiers and has for an object to provide an improved high speed gain control means therefor.

Many amplifiers employing automatic gain control means require that such means be capable of acting very quickly in order to prevent momentary increases in the output of the amplifier upon very sudden increases in the input to the amplifier. It is particularly desirable, for example, in amplifiers employed as modulators in radio transmitters to avoid any possibility of such momentary increases in output in modulating amplifiers, in order to prevent overmodulation in the accompanying transmitter.

In modulating amplifiers, automatic gain control potential is derived from the amplified signal. If sufficient filtering be provided to prevent oscillation and distortion through the amplifier and the automatic gain control circuit, the gain control action is slow unless unusual precaution be taken, such as by providing a balanced or push-pull stage to be controlled by the automatic gain control potential, or by providing a special type of filter. It is accordingly a further object of my invention to provide high speed gain control means for an amplifier in which such unusual precautions need not be resorted to and in which no unusual circuit elements need be provided.

The features of my invention which I believe to be novel are set forth with particularity in the appended claims. My invention itself, however, both as to its organization and method of operation, together with further objects and advantages thereof may best be understood by reference to the following description taken in connection with the accompanying drawing in which the single figure of the drawing represents an amplifier embodying my invention.

In the figure an audio signal from a microphone 10 is amplified successively through electron discharge amplifier devices 11, 12 and 13 to energize a load device 14, which is represented as a resistor but may be any device to be energized by an amplified audio signal, such as a radio transmitter, a loud speaker or the like.

The discharge devices 11 and 12 are represented as having respectively, control electrodes 15 and 16 upon which audio signals from the microphone 10 appear, and additional control electrodes 17 and 18, whose continuous potential may be adjusted to change the gain of the respective discharge device. Conventional means, not described, is employed to connect the discharge devices 11, 12 and 13 in cascade to amplify audio signals from the microphone 10.

The discharge device 13 is of the so-called duplex-diode-triode type in which a diode is provided to rectify the amplified audio signal to produce a unidirectional potential, which may be used for automatic gain control purposes. An anode 19 of the triode section of the device 13 transmits amplified audio signals to the load device 14, and is also connected through a condenser 20 to an anode 21 of the diode section of the device 13. A common cathode 22 of the device 13 is connected through two serially connected resistors 24 and 25 to ground and to the negative terminal of a source 23 of potential. The positive terminal of the source 23 is connected through the load device 14 to the anode 19. The two resistors 24 and 25 are shunted for audio frequency currents by a by-passing condenser 26. The anode 21 is connected through a voltage dividing resistor 27 to ground.

10 The cathode 22 is maintained at an average positive potential with respect to anode 21 by space current flowing through the anode 19, the cathode 22, and through resistors 24 and 25, to delay production of automatic gain control potential across the resistor 27. The anode 21 of the gain control diode rectifier must therefore be made more positive with respect to ground by amplified audio voltage transmitted thereto from the anode 19 through the condenser 20 before the diode rectifier can become conductive and before space current can pass between the anode 21 and the cathode 22. No gain control potential is therefore produced across the resistor 27 until the anode 21 conducts space current at a time 15 when the amplified audio signal rises above a certain predetermined level. This predetermined level may be controlled by resistor 25, which is adjustable. As the audio signal on the anode 19 rises above this level, the gain control potential across the resistor 27 rapidly becomes 20 more negative with respect to ground.

The gain control potential produced across the resistor 27 is a pulsating voltage, and it is applied to the gain control electrodes 17 and 18 of discharge devices 11 and 12 through appropriate filters. For example, the anode 21 is connected through a resistor 29 to the control electrode 18 of discharge device 12, which electrode is bypassed to ground through a condenser 30. The resistor 29 and the condenser 30 operate as a filter to smooth the ripple on the gain control potential across the resistor 27 to a certain extent.

The filter 29, 30 should allow the gain control potential to act very quickly and when so ad-

justed will smooth the ripple on the gain control potential in small degree. The filter should slow the action of the gain control potential only enough to avoid making the volume of the audio signal uniform, so as to impair its intelligibility. In other words, the time constant of the filter 29, 30 should be made just sufficient to avoid distortion of the audio signal. Under such conditions of adjustment, the filter 29, 30 transmits the control potential with sufficient speed to avoid momentary increases in the output of the gain control amplifier.

The gain control electrode 17 of discharge device 11 is connected through a switch 31 and a resistor 32 to an adjustable tap of the voltage dividing resistor 27. The electrode 17 is bypassed to ground through a condenser 33. The resistor 32 and the condenser 33, acting as a filter, cooperate with the electrode 17 in the same way as the filter 29, 30 cooperates with the electrode 18. The filter 32, 33 should operate at the same high speed, that is, with the same short time constant, as the filter 29, 30. An increase in the gain control potential across the resistor 27 decreases the gain of both discharge devices 11 and 12.

Since the filters 29, 30 and 32, 33 are made to allow the gain control potential to act with as high speed, or with as small a time delay, as possible while maintaining audio fidelity, there is a substantial amount of ripple voltage transmitted from the anode 19 of the discharge device 13 through the condenser 20 to the electrodes 17 and 18. This ripple voltage affects the space current in both of the devices 11 and 12. Since these two discharge devices are connected successively in cascade, however, and the ripple voltage of the electrodes 17 and 18 is in phase, the ripple voltage on the electrode 17 affects the space current in the device 12 oppositely to the effect on that space current of the ripple voltage on the electrode 18 of the device 12.

The effect of the ripple voltage on the space current in the device 12, and consequently on the output of the amplifier, is conveniently cancelled by adjustment of the tap on the voltage dividing resistor 27. At the proper adjustment of the tap on resistor 27, the ripple on the electrodes 17 and 18 of the discharge devices 11 and 12 is made to affect the space current in the device 12 in equal amounts as well as in opposite sense.

The two filters 29, 30 and 32, 33 should have the same frequency characteristic measured through the two paths from the resistor 27 to the device 12, respectively, through resistor 29, and through resistor 32 and device 11. In other words, a wave of any particular frequency should be transmitted with a certain time delay from the resistor 27 through the filter 29, 30 to the anode of the device 12, and with substantially equal time delay from the resistor 27 through the filter 32, 33, the device 11, the resistor 34, control electrode 16, and thus to the anode of the device 12. Provision for such equal transmission time in the two paths assures that any ripple voltage on the resistor 27 shall affect the anode of the device 12 in exactly opposite phase through the two paths.

Adjustment of the amount of ripple voltage fed from the resistor 27 through the device 11 to the device 12 may alternatively be adjusted by an adjustable tap of a resistor 34 upon which signals from the device 11 are impressed. The control electrode 16 is connected to the adjustable tap of resistor 34, so that the amount of signal trans-

mitted from the device 11 to the control electrode 16 may be controlled thereby. The amount of signal thus transmitted may be reduced sufficiently, at a particular value of control potential on the resistor 27, so that the ripple voltage transmitted from resistor 27 through the device 11 to the device 12 is equal and of opposite phase to the ripple voltage transmitted through the resistor 29 to the device 12.

While the first of these methods of adjustment is preferred, either is subject to a disadvantage. When the control potential on the resistor 27 changes, the gain of the device 11 changes, so that the amount of ripple voltage transmitted through the device 11 to the device 12 is changed at a different rate from the ripple voltage transmitted thereto through the resistor 29. The ripple voltage transmitted through the device 11 to the control electrode 16 changes least, with respect to the ripple voltage transmitted through the resistor 29, when the device 11 produces maximum amplification therethrough. It is desirable that the gain of device 11 be of the order of thirty times, and that the tap of the resistor 34 be adjusted to apply all of the signal from device 11 to the control electrode 16, so that the amount of the ripple voltage transmitted to the device 11 is adjusted by the tap of resistor 27.

An alternative connection of the amplifier is provided which cancels ripple voltage in the output completely even when the potential across the resistor 27 is changed. This alternative connection exists when the switch 31 is moved to its left-hand position, so that the control electrode 17 is connected through a resistor 35 to ground. A constant bias voltage exists between the electrode 17 and cathode 37 of device 11 produced by flow of space current from cathode 37 to ground through a resistor 38 bypassed for audio frequency currents by a condenser 39. In this position of the switch 31 an adjustable amount of the ripple voltage across the resistor 27 is transmitted through the resistor 32 and through a large condenser 36, connected in shunt to the switch 31, to the control electrode 17.

Adjustment of the amount of ripple voltage with this connection may be made by the adjustable tap either on the resistor 27 or on the resistor 34. It is desirable, however, in order to have maximum gain for the audio signal from the microphone 10, to move the adjustable tap from the resistor 34 up, so as to transmit a maximum amount of signal from the device 11 to the control electrode 16. The adjustment of the ripple voltage is then preferably made by adjustment of the tap of the resistor 27.

By the provision of my improved high speed gain control means in an amplifier including two successive cascaded amplifying devices, so that ripple on the gain control potential affects the signal passing through the two successive devices in equal amounts and in opposite sense, substantially all tendency to feedback with accompanying oscillation or distortion is eliminated, and it is thus made possible to reduce the amount of filtering necessary in the automatic gain control circuit to an amount just sufficient to avoid impairment of the audio signal itself. While the use of two successive cascaded amplifiers is preferred, it is within the scope of my invention to apply a gain control potential to any two cascaded amplifiers while maintaining the phase of the ripple voltage thereon such that it does not affect the amplifier output.

While I have shown a particular embodiment of my invention, it will, of course, be understood

that I do not wish to be limited thereto, since different modifications may be made both in the circuit arrangement and instrumentalities employed, and I aim by the appended claims to cover any such modifications as fall within the true spirit and scope of my invention.

What I claim as new and desire to secure by Letters Patent of the United States is:

1. In combination, a pair of cascade connected alternating current amplifying devices operating in phase opposition, means for adjusting the amplification of each of said devices in response to a gain control potential, means to transmit to at least one of said adjusting means a control potential having an undesired pulsation thereon which produces an undesirable effect on the output of said devices, and means to transmit an amount of said pulsation through the other of said adjusting means sufficient to produce an opposite and substantially equal effect on said output, whereby the effect of said pulsation on said output is substantially eliminated.

2. In combination, an amplifier comprising a plurality of cascade connected electron discharge devices, each having a control electrode, means to transmit a gain control potential having an undesired ripple thereon to at least one of said electrodes, whereby the output of said amplifier is affected undesirably by said ripple, and means to transmit an amount of said undesired ripple to another of said electrodes sufficient substantially to cancel the effect of said ripple on the output of said amplifier.

3. In combination, a pair of cascade connected electron discharge devices each having a control electrode, means to transmit to said control electrodes in parallel a control potential having an undesired ripple thereon, whereby changes in said control potential change the amplification of said devices in the same sense and said ripple

5 affects the output of said amplifier, and means to adjust the amount of said ripple transmitted through one of said control electrodes to said output to produce an effect therein substantially equal and opposite to the effect produced by said ripple transmitted through the other of said control electrodes.

10 4. An amplifier having an output and a pair of cascade connected electron discharge devices, each having control means therefor, means connected to said output to derive therefrom a gain control potential having an undesired ripple thereon, means to apply said potential to at least one of said control means, whereby the gain through said amplifier is adjusted in accordance with said output, and means to transmit said undesired ripple to the other of said control means in an amount sufficient substantially to cancel the effect of said ripple on the output of said amplifier.

15 5. In a signal transmission system, a pair of cascade connected signal amplifying devices, means connected to the output of said devices for rectifying signals amplified therethrough to produce a pulsating unidirectional voltage, means to adjust the amplification of each of said devices in response to a unidirectional voltage, means for impressing said voltage on one of said adjusting means and for delaying the action of 20 said adjusting means in response to changes in said unidirectional voltage an amount sufficient to prevent substantial distortion of said signals, said delaying means producing insufficient delay to smooth said pulsating voltage, and means to impress the pulsations of said voltage on the other of said adjusting means in an amount sufficient to counteract the effect on said output of such pulsations impressed on said one adjusting means.

GEORGE M. BROWN.
